(57) **CLAIM**

The ornamental design for a brassiere, as shown and described.

DESCRIPTION

FIG. 1 is an isometric view of a brassiere in a clasped configuration viewed from the top, right and front sides;

FIG. 2 is a front view of the brassiere;

FIG. 3 is a rear view of the brassiere;

FIG. 4 is a left side view of the brassiere;

FIG. 5 is a right side view of the brassiere;

FIG. 6 is a top view of the brassiere;

FIG. 7 is a bottom view of the brassiere;

FIG. 8 is a sectioned view of the brassiere along the line 8-8 in FIG. 6;

FIG. 9 is a sectioned view of the brassiere along the line 9-9 in FIG. 5;

FIG. 10 is an isometric view of the brassiere in an unclasped configuration viewed from the top, right and front sides;

FIG. 11 is a front view of the brassiere;

FIG. 12 is a rear view of the brassiere;

FIG. 13 is a left side view of the brassiere;

FIG. 14 is a right side view of the brassiere;

FIG. 15 is a top view of the brassiere; and,

FIG. 16 is a bottom view of the brassiere.

The dot-dash broken lines in FIGS. 1-7 and FIGS. 10-16 boundary lines. The boundary lines encircle a central padded region and are disposed within an unpadded region of the brassiere. The brassiere comprises cups that have an unpadded portion and a padded central portion, which are illustrated by the upstanding central portions and the folded or flat surrounding portions.
